ARTIFICIAL FISHING LURE

William O. Williams, Jr., 1309 Lynhurst Drive,
Gastonia, N.C. 28052

Filed July 25, 1974, Ser. No. 491,859

Term of patent 14 years

Int. Cl. D22—05

U.S. Cl. D22—27

FIG. 1 is a perspective view of the basic form of the artificial fishing lure of the present invention;

FIG. 2 is a plan view of the lure of FIG. 1;

FIG. 3 is a front elevation of the lure of FIG. 1;

FIG. 4 is a bottom view of the lure of FIG. 1;

FIG. 5 is a side elevation of the lure of FIG. 1;

FIG. 6 is a rear elevation of the lure of FIG. 1;

FIG. 7 is a perspective view of the lure of FIG. 1 with a design element added to become an alternate form of the artificial fishing lure of the present invention;

FIG. 8 is a plan view of the lure of FIG. 7;

FIG. 9 is a front elevation of the lure of FIG. 7;

FIG. 10 is a bottom view of the lure of FIG. 7;

FIG. 11 is a side elevation view of the lure of FIG. 7;

FIG. 12 is a rear elevation of the lure of FIG. 7;

FIG. 13 is a view similar to FIG. 1 of another modified form with the body plate inverted; and

FIG. 14 is a view similar to FIG. 3 with the body plate inverted.

I claim:

The ornamental design for an artificial fishing lure, as shown and described.
